UNITED STATES PATENT OFFICE.

CLAUDE E. VOUGHT, OF HOUGHTON, MICHIGAN.

COMBINED POKER AND CLINKER TONGS.

Application filed April 23, 1924. Serial No. 708,514.

To all whom it may concern:

Be it known that I, CLAUDE E. VOUGHT, a citizen of the United States, and a resident of Houghton, in the county of Houghton 5 and State of Michigan, have invented certain new and useful Improvements in Combined Poker and Clinker Tongs, of which the following is a specification.

My invention relates to improvements in 10 furnace stoking implements, and it consists of the constructions, combinations and arrangements herein described and claimed.

An object of the invention is to provide an implement which hardly larger than an 15 ordinary furnace poker, yet combines the qualities of a poker and clinker tongs.

Other objects and advantages appear in the following specification, reference being had to the accompanying drawing in which:

20 Figure 1 is a side elevation of the improved implement,

Figure 2 is a longitudinal section thereof,

Figure 3 is a detail section of the locking sleeve,

25 Figure 4 is a cross section on the line 4—4 of Figure 3,

Figure 5 is a cross section on the line 5—5 of Figure 2,

Figure 6 is a cross section on the line 30 6—6 of Figure 2.

In carrying out the invention use is made of a length of seamless tubing 1 which constitutes the stock of the implement. This stock is round for the greater part of its 35 length, but near that end at which the tine 2 appears it is made noncircular, preferably square as shown at 3.

The noncircular portion is bent out at 40 right angles to form the tine 2, the outermost side of the square tubing being removed to provide what might be called a hollow jaw for the reception of the complementary tine or solid jaw 4. The edges of the remaining sides of the hollow jaws 2 are serrated at 5 to coact with similar serrations 6 on the confronting face of the jaw 4 for the purpose of holding clinkers.

A noncircular rod 7 carries the complementary solid jaw 4, the latter being bent 50 out from the former as is readily seen in Figure 2. The rod 7 occupies substantially all of the noncircular portion 3 of the stock. A reach rod 8 screws into the upper end of the noncircular rod 7, and thus makes the 55 connection of the latter with the bar 9 of the handle 10. The rod 8 may be turned

slightly in the treaded hole which it occupies.

Fixed inside of the stock 1 by means of screws 12 is a sleeve 11 in which the handle bar 9 is slideable. The screws 12 are accessible from the outside. The sleeve 11 has a full length slot 14 in which a screw pin 15 works. The pin is carried by the handle bar 9 and keeps said bar from turning so long 65 as the pin occupies the slot.

A notch 16 formed in the upper part of the sleeve 11 receives the pin 15 when the bar 9 is pulled out sufficiently far and given a slight turn to the right. A collar 17, held 70 in place in the stock 1 by a screw 18, stops the outward movement of the handle bar 9 when reached by the pin, and forms a closure for both the slot 14 and notch 16.

The screws pin 15 is driven into the handle bar through a hole 19 (Figures 1 and 4) in the stock 1. This hole is also used to inject oil or grease for lubrication. The handle bar has a threaded hole 20 (Figure 4) into which the pin is screwed. The handle bar 80 is readily brought into position so that the holes 19 and 20 register for the insertion of the screw. The end of the screw comes below the internal surface of the stock 1 so that the handle bar can be turned when 85 required.

Fixed inside of the stock 1 by means of screws 21 is a stop collar 22 against which the lower end of a relatively long spring 23 rests. This spring provides the tension 90 necessary to keep the jaws 2 and 4 closed, either upon each other or upon a clinker. To this end the opposite end of the spring bears against a collar 24.

This collar is shown secured at 95 to the reach rod 8. The reach rod extends through into the end of the bar 9 where it is secured at 26. If it be desired to make the collar 24 integral with the bar 9 and then fasten the reach rod therein such modification may 100 readily be adapted without departing from the particular principle involved.

A spring 27 bears against the collar 24 and the fixed sleeve 11. Obviously the spring collar is movable with the handle rod 105 9. The sole purpose of the spring 27 is to hold the jaws 2 and 4 locked when the pin 15 rests in the notch 16 and the implement is used as a poker.

The operation is as follows: The screw 110 pin 15 must be free to move in the slot 14 when the implement is used as a clinker

tongs. The stock 1 is grasped in the left hand, the handle 10 in the right hand. Keep a firm grip on the stock and push away with the handle. This opens the jaws 2 and 4 so that a clinker may be grasped.

The pressure of the spring against the collar 24 keeps the jaws closed against the clinker, and a further push against the handle releases the clinker.

10 To convert the implement into a poker the user pulls on the handle 10 toward him and pushes on the stock 1 away from him. The handle is given a slight turn to the right when the pin 15 is felt to have reached the 15 collar 17, whereupon the pin enters notch 16. The resulting tension of the short spring 27 keeps the jaws 2 and 4 locked.

Inasmuch as the square jaw rod 7 occupies the square portion 3 of the stock there can 20 be no turning of the one within the other. The necessary turning of the handle bar 9 results in a screwing in or unscrewing of the reach rod in the end of the rod 7.

25 To disassemble the implement it is necessary to remove the screws 12, 18 and the screw pin 15. This loosens the collar 17 and the sleeve 11. The handle 10 is turned until the rod 8 is unscrewed from the jaw rod 7. A pull on the handle then results in 30 the parts coming out all in one.

35 While the construction of the improved implement as herein described and claimed is that of a generally preferred form, obviously modifications and changes may be made without departing from the spirit of the invention or scope of the claims.

I claim:—

40 1. An implement of the character described, comprising a stock having a hollow non-circular portion, a non-circular jaw bar 45 slidable in said portion, complementary jaws formed in the stock and jaw bar, means constituting a bar by which the jaw bar is carried and slid to open and close the jaws, means by which the jaws can be locked together upon turning said bar means, and 50 means including threads by which the connection of the bar means with the jaw bar is made permitting the necessary turning of the bar means.

55 2. An implement of the character described, comprising a tubular stock having a jaw, a jaw bar slidable in the stock and having a complementary jaw, a handle having a bar slidable in the stock, a reach rod connecting the jaw and handle bars, a collar on the handle bar, a collar fixed in the tubular stock, and resilient means including a spring situated between said collars tending to keep the jaws closed.

60 3. An implement of the character described, comprising a tubular stock having a

jaw, a jaw bar slidable in the stock and having a complementary jaw, a handle having a bar slidable in the stock, a reach rod connecting the jaw and handle bars, a collar on the handle bar, a collar fixed in the tubular stock, resilient means including a spring situated between said collars tending to keep the jaws closed, slotted means including a sleeve fixed within the stock and having a recess, and a pin carried by the handle bar riding in the slot and entering the recess upon pulling on and turning the handle to close the jaws, the connection of said reach rod with the jaw rod being threaded and permitting the necessary turning of the handle.

4. An implement of the character described, comprising a tubular stock having a jaw, a jaw bar slidable in the stock and having a complementary jaw, a handle having a bar slidable in the stock, a reach rod connecting the jaw and handle bars, a collar on the handle bar, a collar fixed in the tubular stock, resilient means including a spring situated between said collars tending to keep the jaws closed, slotted means including a sleeve fixed within the stock and having a recess, a pin carried by the handle bar riding in the slot and entering the recess upon pulling on and turning the handle to close the jaws, and resilient means including a spring between the handle bar collar and sleeve to hold the pin in said recess and keep the jaws locked.

5. An implement of the character described, comprising a tubular stock including a non-circular portion terminating in a serrated jaw, a collar fastened in the opposite end of the stock, a slotted sleeve fixed in the stock abutting the collar and having a recess in the adjacent edge in communication with the slot, a collar fixed in the stock, a handle having a handle bar occupying the sleeve and having a pin riding in the slot keeping the handle from turning, a reach rod secured to the handle bar, extending through and guided by said fixed stock collar, a collar situated at the juncture of said bars, a non-circular movable jaw rod occupying said non-circular stock portion and having a complementary serrated jaw, a loosely threaded connection between the reach and jaw rods permitting turning of the handle when the pin is raised to registration with the recess, a spring between the handle bar, collar and sleeve holding the pin and recess in engagement and the jaws locked, and a spring between said collar and the stock collar supplying tension to the movable jaw.

CLAUDE E. VOGHT.
